US0D1035613S

(12) **United States Design Patent** (10) **Patent No.:** **US D1,035,613 S**
(45) **Date of Patent:** **** Jul. 16, 2024**

(54) **HEADPHONES**

(71) Applicant: **Logitech Europe S.A.**, Lausanne (CH)

(72) Inventors: **Jeremy Paul Burgess**, San Jose, CA (US); **James Lee Kwon**, Oakland, CA (US)

(73) Assignee: **Logitech Europe S.A.**, Lausanne (CH)

(**) Term: **15 Years**

(21) Appl. No.: **29/914,188**

(22) Filed: **Oct. 13, 2023**

Related U.S. Application Data

(63) Continuation of application No. 29/801,570, filed on Jul. 29, 2021, now Pat. No. Des. 1,007,462.

(57) **CLAIM**

The ornamental design for headphones, as shown and described.

DESCRIPTION

FIG. 1 is a perspective view of headphones showing my new design;

FIG. 2 is another perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The broken lines on the headphone headband represent the bounds of the claimed design while all other broken lines depict portions of the headphones that form no part of the claimed design. All of the broken lines form no part of the claimed design.

1 Claim, 6 Drawing Sheets
